UNITED STATES PATENT OFFICE

171,716

SAILBOAT FOR CHILDREN

Robert E. Lane, Jacksonville, Fla.

Application May 5, 1953, Serial No. 24,861

Term of patent 14 years

(Cl. D34—15)

To all whom it may concern:

Be it known that I, Robert E. Lane, a citizen of the United States, residing at Jacksonville, Florida, have invented a new, original, and ornamental Design for a Sailboat for Children, of which the following is a specification, reference being had to the accompanying drawing, forming a part hereof.

Fig. 1 is a side elevational view, to a reduced scale, of a sailboat for children, showing my new design; and

Fig. 2 is a perspective view thereof.

I claim:

The ornamental design for a sailboat for children, as shown.

ROBERT E. LANE.
